BENJAMIN GARVIN AND R. J. PETTIBONE, OF OSHKOSH, WISCONSIN.

Letters Patent No. 71,804, dated December 8, 1867.

IMPROVEMENT IN FEED-WATER HEATERS FOR LOCOMOTIVES.

The Schedule referred to in these Letters Patent and making part of the same.

TO ALL WHOM IT MAY CONCERN:

Be it known that we, B. GARVIN and R. J. PETTIBONE, of Oshkosh, in the State of Wisconsin, have invented a Water-Heater for Locomotives; and we do hereby declare that the following is a full, clear, and exact description of the same, reference being had to the accompanying drawings, and letters marked thereon, making a part of this description, in which—

Figure 1 is an elevation of our heater.

Figure 2, a sectional elevation of the same.

Figure 3, a plan view, showing the under side of the steam-chamber and the pipes.

The nature of our invention consists in arranging a series of pipes in the smoke-stack, communicating with a double steam-chamber, the pump, and feed-pipes, and is designed to heat water by means of the exhaust steam before it enters the boiler. We know that feed-water heaters have been used both for stationary engines and those which are portable, and therefore do not claim the use of exhaust steam for-heating feed-water.

In order to give a correct understanding of our invention, we have marked corresponding parts with similar letters, and will now give a detailed description.

H represents the collar which is usually attached to the common locomotive-boiler. A double steam-chamber, B C, is covered with a concave cap, A, a little smaller than the smoke-stack J, shown by red lines in fig. 1, for the purpose of giving a suitable draught, and is supported by means of rods, G G G, rigidly attached to said collar, and to the steam-chambers above mentioned. A series of pipes, F, is made to enter the chamber C, fig. 2, one pipe, F, same figure, being arranged to communicate with the upper chamber, B, by which means the water is made to enter all of the pipes and chambers, and thus become heated before entering the boiler. The pipe E is used to supply the heater, and the pipe D for supplying the boiler, said pipes being arranged, by means of screw-threads K K, so as to be attached to any common pipes, of suitable length, in the usual manner.

It is not necessary that there should be two chambers in order to heat water, nor is it materially essential that the inner pipes I, fig. 2, be used, but the heater will have a much greater surface to be acted upon when arranged as shown in the drawing.

The steam can be made to enter the pipe F, fig. 1, or any pipe communicating with the upper chamber B. We use, in the construction of the heater, material similar to that used in the manufacture of boilers, and secure the joints and connect the pipes in the same manner.

Having thus fully described our device, what we claim, and desire to secure by Letters Patent, is—

The combination of the pipes E D and F F F, &c., steam-chambers B C, arranged inside of a smoke-stack and over the collar H, substantially as and for the purpose herein specified.

BENJAMIN GARVIN,
R. J. PETTIBONE.
